[57] **CLAIM**

The ornamental design for a window blind headrail, as shown and described.

DESCRIPTION

FIG. 1 is a perspective view of a window blind headrail showing my new design;
FIG. 2 is an enlarged front elevational view thereof, shown broken away for ease of illustration;
FIG. 3 is a top plan view thereof;
FIG. 4 is a rear elevational view thereof;
FIG. 5 is a bottom view thereof;
FIG. 6 is an end elevational view as seen from the left in FIG. 1, the other end being a mirror image thereof; and, FIG. 7 is a cross-sectional view taken on the line 7—7 of FIG. 1, showing the cross-sectional configuration thereof.

FIG. 1

FIG. 2

FIG. 3

FIG. 4

FIG. 5
